UNITED STATES PATENT OFFICE.

THOMAS A. SAMMONS, OF DAYTON, OHIO.

PERMUTATION-LOCK.

1,158,860.

Specification of Letters Patent.

Patented Nov. 2, 1915.

Application filed February 23, 1915. Serial No. 9,958.

To all whom it may concern:

Be it known that I, THOMAS A. SAMMONS, a citizen of the United States, residing at Dayton, in the county of Montgomery and State of Ohio, have invented certain new and useful Improvements in Permutation Locks, of which the following is a specification.

My invention relates to locks of the permutation type. It is applicable as a lock for doors, drawers or chests, or as a lever lock for securing in adjusted position any oscillatory lever or operating arm, for example, the operating lever of a railway switch or the control lever of a motor cycle or automobile. It is further applicable as a lock for electric switches such as the switch controlling the ignition system of an automobile or motor cycle or other electric circuit.

The object of the invention is to simplify the structure as well as the means and mode of operation of such devices whereby they will not only be cheapened in construction, but will be more efficient in use, positive in action, easily operated, capable of operation in the dark, and unlikely to get out of repair.

A further object of the invention is to provide a form of permutation lock which obviates the use of knobs, push buttons, levers or other external movable parts, necessary to be manipulated by the operator each time the locking bolt is to be shifted. Such devices offer temptation to unauthorized persons to tamper with the locking mechanism. In the present instance the lock is operated by a single operation regardless of the number of tumblers or the figures of the combination.

A further object of the invention is to provide a lock in which the locking bolt is automatically locked in either its engaged or disengaged position.

With the above primary and other incidental objects in view, as will more fully appear in the specification, the invention consists of the features of construction, the parts and combinations thereof, and the mode of operation, or their equivalents, as hereinafter described and set forth in the claims.

Referring to the drawings, Figure 1 is a perspective view of the lock applied to the control lever of an automobile. Fig. 2 is a

perspective view of the supporting frame 55 for the lock attached to the lever but from which the lock has been removed. Fig. 3 is a perspective view of the lock removed from the supporting frame. Fig. 4 is a transverse sectional view of the lock supporting frame 60 illustrating its mode of connection with the operating lever. Fig. 5 is a side elevation, partly broken away, of the lock applied to an electric switch such as the control switch for a motor ignition system. Fig. 5^a is a 65 modification of the electrical contact shown in Fig. 5. Fig. 6 illustrates the application of the lock to a door such as a vault or safe door. Fig. 7 is a vertical sectional view of the lock housing with the mechanism 70 enclosed therein. Fig. 8 is a vertical sectional view on line *ωω* of Fig. 7. Fig. 9 is a similar vertical sectional view on line *γγ* of Fig. 7. Fig. 10 is a similar vertical sectional view on line *ζζ* of Fig. 7. Fig. 11 is a detail sectional view similar to Fig. 8 showing the locking tumblers in operated or releasing position with the releasing key engaging therewith. Fig. 12 is a detail perspective view of the main frame of the lock housing. Fig. 13 is a sectional plan view of the lock housing interengaged with the supporting frame. Fig. 14 is a detail perspective view of the closure slide for the lock housing and the locking bolt by which the closure slide is secured in adjusted position and the lock housing secured to the supporting frame. The said parts are shown in unlocked position. Fig. 15 is a detail view of the parts shown in Fig. 14, the locking bolt 80 being shown in locking position by dot and dash lines and in released position by dotted lines and in an intermediate position, in which the housing is released, by solid lines. Fig. 16 is a detail perspective view of the locking bolt. Fig. 17 is a detail perspective view of the tumblers, the detent or dog being shown in dotted lines and the position of the locking bolt being shown in dot and dash lines. Fig. 18 is a perspective view of the release key. Fig. 19 is a longitudinal sectional view of the release key. Fig. 20 is a detail perspective view of the frame of the release key, the operating parts being removed. Fig. 21 is a perspective view of the locking slide of the release key. Fig. 22 is a detail perspective view of the lock mechanism applied to a snap lock.

Like parts are indicated by similar characters of reference throughout the several views.

The lock forming the subject matter hereof involves a reciprocatory lock bolt which not only locks the control lever, the door, lid or other movable member, to which it is applied, in its adjusted position, but it also locks the housing or case for the lock mechanism to the supporting structure and furthermore locks the closure slides of the housing in closed position. Therefore the bolt not only prevents the operation of the movable member to which it is applied, such as the lever, door, or lid, but it also prevents the detachment of the lock mechanism and further prevents the opening of the housing or case of the lock mechanism until the lock itself has been released by proper manipulation of its parts.

The locking bolt is controlled by a plurality of tumblers which may be variously arranged to change the combination or formula by which the lock may be opened. The construction is such that a great number of tumblers or locking units may be manipulated as easily and as quickly as a few locking members. This affords a wide range of combinations and affords no greater difficulty or requires no more extended operation to employ a combination involving high numbers than low numbers.

The lock shown in the drawings embodies six tumblers or locking units which enables the use of nine hundred and ninety-nine thousand nine hundred and ninety-nine different combinations. As shown in the drawing, the combination required to release the locking bolt is 586472. This number may be changed by merely a rearrangement of the tumblers or locking units or by locating the release notch at different points in the respective units. The lock is adapted to be released by a release key, also of the permutation type, having a plurality of tumblers or units which may be previously set to the combination necessary to operate the lock, and by which the lock is released by a single operation.

When permutation locks, involving push buttons, levers, or knobs, which must be repeatedly manipulated in order to release the lock, are employed the tendency is to use combinations containing low numbers thereby reducing the number of manipulations necessary. This increases the ease with which the lock may be opened by unauthorized persons who may start with No. 1 and operate the lock on successive numbers until the proper combination has been reached. In the present instance this difficulty has been obviated by providing means whereby combinations containing the high numbers are equally as easily operated as those containing low numbers. This is accomplished

by means of the permutation key, before mentioned, which may be previously set to the desired combination and retained in that position ready to release the lock by a single operation. However, if the operator fears that the key may fall into the hands of an unauthorized person the combination of the key may be returned to 0 or otherwise thrown out of the proper combination necessary to release the lock in which case it must be readjusted before it is again used.

Referring to Figs. 1 to 4, 1 is an automobile control lever movable in the usual H slot 2 in a suitable sector or guide plate 3, in which it is desired to lock the lever in normal or neutral position in the transverse portion of the H slot. Secured to the movable lever 1 by means of clevises 4 is a supporting plate or frame 5 having at its opposite edges longitudinally disposed gibs or guides 6 in which the housing of the lock mechanism slides. The lock mechanism housing is provided with a suitable flange which engages within the recessed gibs or guides. At its upper end the supporting frame or plate 5 is provided with a transverse groove or recess 7 in which the closure plate of the lock housing engages to prevent the withdrawal of the lock from the gibs 6. The clevises 4 are attached to the supporting plate or frame by screws 8 which extend through the supporting plate or frame and into the ends of the clevises. These screws are located in the supporting plate at such points that they will be covered and concealed by the lock housing when the latter is in adjusted position. In addition to the clamping of the operating lever 1 to the supporting plate by means of the clevises, the supporting plate is further attached against longitudinal movement upon the handle by means of a cupped or dog pointed set screw 9 which engages the edge of the lever 1 and is so located in the plate that it also will be concealed and protected by the lock housing. It will thus be seen that it is necessary to remove the lock housing from the supporting frame or plate before the latter can be adjusted to or removed from the control lever 1.

The lock housing comprises a trough-like or open-sided and open ended frame as shown in detail in Fig. 12. At its lower end this frame is provided with transverse grooves or guides 11 in which slide a removable bottom plate 12. (See Figs. 1, 7 to 10, inclusive). The bottom plate 12 is provided with a transverse groove or recess 13 which registers with longitudinal grooves 14 located in the inner faces of the side walls 120 of the housing frame and adjacent to the edges thereof. These longitudinal grooves or recesses 14 receive a sliding front plate 15 which, when properly adjusted, projects into the transverse groove or recess 13 in the 125

bottom plate 12 and thereby prevents the withdrawal of the bottom plate 12 until the front plate 15 has first been elevated. Thus the front plate 15 locks the bottom plate 12 in adjusted position.

At its upper end the frame 10 is provided with transverse grooves or recesses 16 in which slides a cover or closure plate 17 which projects over the upper edge of the front plate 15 and prevents the elevation thereof until the cover or closure plate has been removed. (See Figs. 1, and 7 to 10, inclusive). The cover or closure plate 17 thus locks the front plate 15 which in turn locks the bottom plate 12 as before mentioned. Furthermore, the top or closure plate 17, when in its inner or adjusted position, engages in the transverse groove or recess 7 in the upper edge of the supporting plate or frame 5 thereby locking the housing against withdrawal from the gibs or guides 6. The top or closure plate 17 is in turn locked against withdrawal from the recess 7 in the supporting plate or frame by the locking bolt hereinafter described. There is thus provided a chain of locks comprising the main locking bolt which locks the top or cover plate 17 which in turn, by its engagement in the recess 7, locks the housing against removal from its supporting plate or frame 5 and furthermore, by its extension over the front plate 15, locks the front plate 15 in adjusted position, which in turn by its engagement in the groove 13 locks the bottom plate 12. The housing 10 is further provided with parallel spaced grooves or recesses 18 and 19 in its inner walls to receive partition plates 20 and 21 (see Fig. 7) which form guides for the reciprocating tumblers or locking units and the plungers hereinafter mentioned. Intermediate the grooves 18 and 19 in the side walls of the housing there are provided other grooves or recesses 22 of comparatively short extent with which a transverse slot 23 in the lid or cover plate 17 registers when the said plate is in its adjusted position. The release key is introduced through the slot 23 and reciprocates in the short grooves or recesses 22 to unlock the mechanism. Located adjacent to the back wall of the housing frame are longitudinal grooves or recesses 24 in which engage lateral flanges 25 upon the reciprocating locking bolt 26 which is adapted to reciprocate within the housing frame in said grooves or recesses 24. For engagement with the medial tongue of the guide plate 3, the lower edge of the locking bolt is provided with a bifurcated head 27 which engages over said tongue to hold the lever 1 in its neutral position. It is to be understood that this bifurcated end is merely incidental to this particular use of the device and that the locking bolt head 25 may be of any suitable or desired shape ac-

cording to the shape of the keeper or socket to be engaged thereby.

Adjacent to its lower end the locking bolt 26 is provided with an inward projecting stud 28 having a head 29 projecting into a slot 30 in the rear wall of the housing frame. A retracting spring 31 is attached at one end to the stud 28 and at its upper end to a stud 32 projecting from the partition plate 21. This retracting spring 31 tends to elevate the locking bolt 26 when said bolt is released from the detent or dog.

Adjacent to its upper end the locking bolt 26 is provided with a lug or shoulder extension 33 with which it is engaged, by a detent 80 or locking dog. The locking dog comprises a transverse head 34 supported by pivotally connected parallel arms 35 hinged at their lower ends to a suitable lug or pivot head 36 carried by the partition plate 21. The object in bifurcating the detent or locking dog or providing the double arms 35 therefor is to provide a sufficient clearance space intermediate said arms for the retracting spring 31 of the locking bolt which is located intermediate the arms. The relation of these parts is best shown in Fig. 9.

When the locking bolt is in its depressed or operated position, the transverse head 34 of the detent or locking dog engages the upper edge or shoulder of the lug or extension 33, as shown in Fig. 7, to hold the bolt in adjusted position. However, when the bolt 26 is released and retracted by the spring 31 the transverse head 34 of the detent or locking dog will engage beneath the lower edge or shoulder of the lug or extension 33, as shown by dotted lines in Fig. 7, and by dot and dash lines in Fig. 17, to lock the bolt in its elevated or inoperative position.

The locking dog or detent is provided with springs 37 which tend to oscillate the detent or dog away from the bolt and out of engagement with the lug or extension 33. Thus the normal tendency of the detent or locking dog is to release the bolt and allow it to be elevated by the retracting spring 31. The releasing movement of the detent or dog, however, is prevented by its engagement with the locking tumblers or units 39 loosely mounted to reciprocate intermediate the partition or guide plates 20 and 21. The partition or guide plate 21 is provided with a recess 40 through which the transverse head of the detent or dog projects into contact with the tumblers or locking units 39.

The locking tumblers or units are shown in detail in Fig. 17. Each comprises a short bar having in one edge a notch or recess 41. To extend the possible combinations to be made with one set of tumblers or locking units the locking units are preferably provided with notches 41 in each edge whereby the locking unit may be reversed, the 120

notches, of course, being located at different points in relation with the length of the unit. Thus in Fig. 7 the locking unit has a notch in one edge in the No. 4 position and in the opposite edge in a number 8 position. In Fig. 17 the locking unit nearest to the observer is provided with a notch in the number 2 position in one edge and in the number 6 position in the opposite edge. Thus by reversing the unit either position number may be employed in the combination. There are a plurality of these units employed. In the drawings, six have been shown, each provided with notches in different positions in relation to the ends of the unit. These locking tumblers or units are arranged side by side in the space intermediate the partition or guide plates 20 and 21. The combination may not only be changed by reversing these units in their positions, but the positions of the units themselves may be interchanged. By changing the order of the units the combination may be further varied.

To facilitate the interchange of the locking units or tumblers, they are provided at their upper ends with small notches 42 by which they may be engaged to lift them from their positions between the partition or guide plates 20 and 21. These locking tumblers or units are loosely supported upon the upper ends of depressible plungers 43 also mounted to reciprocate between the partition or guide plates 20 and 21. There is provided one depressible plunger 43 for each locking unit or tumbler. The plungers 43 are each provided with a shoulder or offset 44 which engages the lower end of the partition or guide plate 20 and forms a stop to limit the upward movement of the plunger. A retracting spring 45 is connected at one end to a stud 46 carried by the plunger 43, at its upper end to a stud 47 projecting from the partition or guide plate 20. There is a retracting spring 45 provided for each of the plungers 43. (See Fig. 10).

As before stated, the detent or dog is held against movement under the influence of the springs 37 by the engagement of the transverse head 34 with the un-notched portion of the locking tumblers or units 39. By depressing the tumblers or units 39 each a different distance against the tension of the retraction springs 45 of the plungers 43, the notches or recesses 41 in the tumblers or units 39 are brought into alignment one with another and also into registry with the transverse head 34 of the detent or locking dog. As soon as this occurs the detent or locking dog, acting under the influence of its springs 37, will move into the aligned registered notches 41 of the locking units and out of the path of the lug or extension 33 on the locking bolt. The bolt thus released will be elevated under the influence of the re-

tracting spring 30, or, if already retracted, will be freed whereby it may be depressed against the tension of said spring. As soon as pressure upon the tumblers or units 39 is relieved, the plunger springs 45 will retract the plungers and thereby elevate the tumblers or units to normal position. The notches 41 are thus returned to unaligned positions and the dog caused to engage an unnotched portion of the units.

It is to be noted that the lower sides of the notches or recesses 41 of the tumblers or units are inclined or beveled. Engagement of these beveled edges with the transverse head 34 of the detent or locking dog acts as cams upon said head to force the head outward away from the tumblers or units against the tension of the spring 37 and into the path of the lug or extension 33 upon the locking bolt. Thus whenever the tumblers or locking units are released from their depressed position, in which the notches 41 are aligned, the detent or locking dog is automatically thrown into the path of the locking bolt lug 33 thereby locking the said locking bolt in either its depressed or elevated position.

If so desired, a permanent key having shoulders or offsets thereon corresponding with the positions of the notches 41 in the tumblers or units 39 may be employed. When such key is inserted into the slot 23 in the cover plate or lid 17 and reciprocated downward through the guide grooves or recesses 22, the tumblers or units and the corresponding plungers are depressed to such extent as to align or register the notches 41 and release the dog or detent. This would constitute a permutation lock, the tumblers of which are interchangeable. Upon changing the combination by interchanging the tumblers a permanent key of different shape would be required. However, if possession of the permanent key was secured by an unauthorized person, the lock could be readily operated. To obviate this difficulty there is provided for use with the lock as before described a permutation key, shown in Fig. 11 and in Figs. 18 to 21 inclusive. This key comprises a frame 50, shown in detail in Fig. 20, which comprises two parallel bars or fingers 51 connected by a transverse head 52 at one end and further connected at a medial point by a transverse plate or offset head 53, one edge of which is inclined or provided with a cam surface 54.

Loosely mounted in the frame 50 intermediate the fingers 51 are a plurality of longitudinally movable plungers 55, one for each locking tumbler or unit 39. Each of these plungers 55 has adjacent to its outer end a notch 56 in which may be engaged any pointed implement to move the plunger longitudinally in the frame. Adjacent to the rear extremities the plungers 55 are pro-

vided with a plurality of notches or ratchet teeth 57 which are located on that side of the plunger adjacent to the transverse plate or head 53. Mounted to reciprocate upon the frame 50 intermediate the terminal head 52 and the medial head 53 is a slide 58 carrying a plurality of spring fingers 59, one for each of the reciprocatory plungers 55. These spring fingers 59 engage the notches or ratchet teeth 57 of the corresponding plungers 55. At its extremity the slide 58 is provided with teeth or detents 60 which engage notches 61 in the fingers 51 of the main frame 50, located therein adjacent to the transverse head 52.

As before stated, the spring fingers 59 of the slide 58 engage the notches or ratchet teeth 57 of the corresponding plungers 55. When the slide is in its forward or advanced position the fingers 59 project beneath the inclined or cam surface 54 of the transverse medial head 53 by which the fingers are locked in engagement with the notches or ratchet teeth 57 of the plungers 55, thereby preventing longitudinal movement of the plungers. The slide 58 is held in its advanced or locked position by the engagement of the detents or teeth 60 thereof in the notches 61 in the fingers 51 of the frame. However, by tilting the slide 58 to raise the rear end thereof, the detents or teeth 60 of the slide are disengaged from the notches 61 of the frame whereupon the slide may be moved rearward a sufficient distance to disengage the spring fingers 59 from beneath the inclined or cam surface 54 of the transverse medial head 53. This unlocks the plungers and the spring fingers 59 are thereupon permitted to vibrate as the plunger is pulled outward. When the plungers are all adjusted outward to the proper position to correspond with the locking units or tumblers 41, the slide 58 is reciprocated forward to again lock the plungers in adjusted position by the cam action of the surface 54 pressing the fingers into engagement with the plungers. It is held in advanced position by the engagement of the teeth or detents 60 in the notches 61. If, however, it is desired to destroy or throw out the combination setting of the key, the rear end of the slide is elevated, as before described, to disengage it from the notches 61 whereupon it is reciprocated rearward to disengage the spring 59 from the cam surface 54 whereupon the forward end of the slide is then elevated to disengage the fingers 59 from the notches 61 of the plungers, allowing the plungers to be pressed rearward, or if the key is held in a vertical position, the plungers will return to normal or "0" position by gravity.

To prevent the accidental disengagement of the slide from the frame or the spring fingers 59 from the plungers the slide 58 is

subjected to the tension of a flat spring 62 which is bent into a substantially U shaped form. One side of this spring plate is secured to the frame 50 by screws 63, as shown in Fig. 11. The other side of the spring plate or casing is free and bears upon the slide 58 tending to press it into engagement with the frame at one end and into engagement with the plungers at its opposite end. This spring plate forms a housing for the key mechanism. It will be understood that the plungers can be adjusted in the frame to different positions which will correspond with the notches 41 in the tumblers or units 41 of the lock mechanism.

When the key is inserted through the slot 23 in the cover plate 17 the fingers 51 enter the guide slots or grooves 22 in the side walls of the housing frame while the plungers 55 engage the corresponding tumblers or locking units to depress said locking units against the tensions of the plunger springs 45 to align the notches 41. If the plungers within the key have not been properly adjusted the units will not be depressed to the proper position and the notches will not be aligned. Therefore the lock will not be released unless the proper combination has been set upon the key. The combination set upon the key is the one corresponding to the arrangement of the locking units or tumblers within the locking mechanism.

If desired, the key plungers may be thrown out of adjustment after each operation of the lock by the manipulation of the slide 58, before described. If, however, there is no danger of the key falling into the hands of an unauthorized person, the combination setting of the key may be retained for the day or for such period of time as may be desired. However, whenever the operator so desires he may throw off the key combination and it can be reset again only by a person who has knowledge of the combination or arrangement of the locking tumblers or units within the locking mechanism.

In setting the key plungers the notches 56 are engaged by any pointed instrument and the plunger pushed out to the desired extended position. The notches or teeth 57 in the plunger correspond with the different positions of the notches 42 in the locking unit. By counting the clicks as the spring finger 59 passes from one notch 57 to another the relative positions of the key plungers may be determined, enabling the device to be operated in the dark.

Referring now to Figs. 14, 15, and 16, the locking bolt 26 is provided at its upper end with an extension 64 which normally projects above the cover or locking or closure plate 17. This extension 64 is provided with oppositely disposed notches 65 forming a neck which registers with the lid or cover plate 17 when the lock is at a medial point

80

130

in its path of travel. At this medial point, when the notches 65 are alined with the cover or closure plate 17, the detent or dog 34 is engaged in the alined notches 41 of the tumblers or units upon one side and at the opposite side bears upon the face of the lug or extension 33. The cover or closure plate 17 is provided at its rear edge with a T shaped slot 66 the transverse portion of which corresponds with the cross section of the head or extension 64 of the locking bolt 26. The lateral or narrow portion of the T shaped slot is substantially equal in width and is alined with the neck formed by the lateral notches 65 in the locking bolt. The construction is such that when the locking bolt is in its medial position, *i. e.*, at a point midway between its locked and unlocked position, the cover lid or closure plate 17 may be reciprocated past the bolt. In such case the narrow portion of the slot 66 passes through the notches 65 until the wide portion of the slot is alined with the bolt. When the locking bolt 26 is in either its depressed or elevated position, the lateral notches 65 will be out of alinement with the cover plate 17 and the portions of the extension 64 on either side of the notches will be engaged within the wide portion of the T shaped slot thereby preventing the withdrawal of the cover plate until the locking plunger is moved to its medial position.

In Fig. 15 the locking bolt has been shown by solid lines alined with the cover plate, in which position the cover plate may be withdrawn. In dotted lines the locking bolt has been shown in its elevated position whereby the cover plate is locked against withdrawal by that portion of the extension beneath the lateral notches 65. The depressed position of the locking bolt is shown by dot and dash lines in which position the portion of the extension above the lateral notches 65, engaging in the wide portion of the T shaped slot, locks the cover plate against withdrawal. In its innermost or locked position the rear edge of the lid or cover plate 17 engages in the transverse groove 7 in the supporting frame or plate as before described. Therefore, when the locking bolt is in either its released or its operated position the housing is securely locked to the supporting frame or plate 5.

In Fig. 5 there has been shown an application of the locking mechanism, before described, to the control of an electric switch. In this construction the supporting plate or frame 5 is formed with a hollow or recess 67 in which is located an ordinary flat spring contact 68. The spring contact 68 is insulated from the supporting frame or plate and is provided at its free end with a stud or contact point 69 which projects through an opening 70 in the face of the supporting plate or frame 5. The stud or contact fin-

ger 69 extends beyond the face of the supporting frame or plate 5 into the slot 30 in the rear wall of the lock housing in which position it is in the path of the head 29 of the stud or pin 28 carried by the locking bolt. One side of the electric switch to be controlled is connected to the spring contact 68, the other side of the circuit being connected to the supporting frame or plate from which the spring contact is insulated. The lock housing, being in direct contact with the supporting frame or plate 5, forms one terminal of the circuit. In this construction the head 29 of the stud 28, carried by the locking bolt, will engage the contact stud or finger 69, carried by the spring contact 68, when the bolt is depressed, thereby closing the circuit. The locking bolt being secured in either its elevated or depressed position by the mechanism before described, the circuit cannot be closed without first operating the lock mechanism to release the bolt. The bolt having been thus released and depressed, the circuit is closed and cannot be opened by the elevation of the bolt until the lock mechanism is again manipulated.

It is obvious that any suitable switch mechanism may be employed and applicant does not wish to confine himself to the particular switch shown in the drawing. For example, in lieu of the single spring contact 68, two contact blades 71 and 72, as shown in Fig. 5^a, may be employed which are pressed into engagement one with the other by the engagement of the stud head 29 with a suitable projection carried by one of these blades. In this construction the supporting frame or plate 5 and the lock housing would form no part of the electric circuit. To prevent the closing of the circuit by unauthorized persons by means of an implement such as a knife blade inserted into the slot 30 from the bottom of the housing, thereby either depressing the contact finger or stud or making electrical contact between the circuit terminals without first manipulating the lock mechanism, there is provided upon the rear face of the locking bolt a projecting lug 73 which, when the locking bolt is in its elevated position, closes the lower end of the slot 30, as shown in Fig. 3. It will be understood that when the lock is used to control an electric circuit the bifurcated head on the lower end of the bolt is omitted.

In Fig. 6 there is shown a construction such as is usually found in safe or vault doors in which 75 is the door which engages the jamb or frame 76. A reciprocating locking bolt 77, controlled by the rotary handle, serves to lock the door in closed position. The locking mechanism, heretofore described, is inserted in the door frame as indicated at 79, in such position that the bolt of the locking mechanism will engage 130

the door bolt 77 to prevent its withdrawal under the influence of the handle 78.

In Fig. 22 there is shown a modification of the locking mechanism, the only change 5 being in the arrangement of the locking bolt. The tumblers, the plungers, and the retracting springs are exactly the same as before described. On its inner side the locking dog engages the notches in the tumblers or units in the same manner as before 10 described. Likewise it is spring actuated toward the locking tumblers by a spring 37^a corresponding to the springs 37, as before mentioned. In lieu, however, of the reciprocating locking bolt of the previous construction, there is employed in this snap lock an oscillatory hook shaped bolt 79 pivoted concentric with the oscillatory dog or 15 detent. In this form of device the detent dog 35 is provided with lugs or extensions 20 81 which engage the pivoted bolt 79 and carry the bolt with the dog in its inward movement under the influence of the spring 37^a when the notches in the tumblers or 25 locking units have been brought into registry with the head 34 of the dog. This inward oscillation of the locking bolt 79 in unison with the dog or detent under the influence of the spring 37^a disengages the hook 30 bolt 79 from its keeper 80. Of course this can only occur when the locking unit has been properly adjusted. The locking bolt 79, however, is capable of oscillatory movement inward independent of the dog or 35 detent 35 against the tension of the spring 82. This spring 82 is secured to the hook bolt 79 and bears at its free end upon the dog or 40 detent 35 and tends to maintain the lock bolt 79 in contact with the lugs or extensions 45 81 of the dog or detent. However, when the dog or detent is in its normal or locked position and the keeper 80 is thrust downward the interengagement of the cam face of the keeper 80 with that of the lock bolt 79 causes 50 the bolt 79 to be oscillated inward independent of the dog or detent 35 against the tension of the spring 82 until the shoulder of the keeper has passed that of the lock bolt, 55 whereupon the spring 82 will return the lock bolt into engagement with the shoulder of the keeper. This construction is particularly desirable for chests or doors or other constructions employing relatively movable parts which tend to approach or recede one 60 from the other.

From the above description it will be apparent that there is thus provided a device of the character described, possessing the particular features of advantage before enumerated as desirable but which obviously is susceptible of modification in its form, proportion, detail construction or arrangement of parts, without departing from the principle involved or sacrificing any of its advantages.

While in order to comply with the statute the invention has been described in language more or less specific as to certain structural features, it is to be understood that the invention is not limited to any specific details, 70 but that the means and construction herein described comprise but one mode of putting the invention into effect and the invention is therefore claimed broadly in any of its possible forms or modifications within the 75 scope of the appended claims.

Having thus described my invention, I claim:

1. In a permutation lock, a housing, a reciprocatory bolt, a detent therefor, a plurality of independently movable reciprocatory plungers, and a plurality of independent interchangeable locking units one for each plunger upon which the locking units rest, each locking unit having a recess therein, 80 the recesses of the different units being adapted to be alined by the independent adjustment of the locking units to different relative positions thereby permitting the detent to enter into the alined recesses to release the bolt. 85

2. In a permutation lock, a housing, a reciprocatory bolt, a detent therefor, a plurality of spring actuated independently depressible plungers, a differently notched head for each plunger, the notched heads of the plungers being interchangeable, the notches of said plunger heads being alined by the unequal depression of the plungers to 95 permit the movement of the detent to release the bolt. 100

3. In a permutation lock, a housing, a reciprocatory bolt, a detent therefor, a plurality of spring actuated independently depressible plungers, an independent locking member resting on each plunger, each locking member having a differently located notch in the opposite sides thereof, the locking members being reversible whereby different combinations may be effected, the plungers 105 and locking members being depressible in unison to aline the notches to permit the disengagement of the detent from the bolt. 110

4. In a lock mechanism, a movable bolt, oppositely disposed shoulders on the bolt, a detent adapted to engage either of the shoulders to maintain the bolt in either locking or unlocking positions, a spring tending to move the detent out of engagement with the bolt and a plurality of independent movable locking units normally extending into the path of the detent and movable therefrom through different predetermined degrees of movement. 115

5. In a permutation lock, a locking bolt, 120 a detent therefor, a plurality of independently depressible spring actuated plungers, and a plurality of separate interchangeable locking members one for each plunger moving in unison with the plungers controlling 125 130

the movement of the detent into and out of engagement with the bolt.

6. In a permutation lock, a main housing, a locking bolt, locking means controlling the bolt, a support to which the housing is detachably secured by the operation of said locking bolt, and attachment means for said support normally concealed and rendered inaccessible by said housing.

10. 7. In a permutation lock, a housing, a locking bolt, locking means within the housing controlling the bolt, a series of reciprocatory closures for said housing, each succeeding closure of the series being adapted 15 to extend into the path of the preceding closure, the bolt normally extending into the path of the final closure of the series.

8. In a permutation lock, a housing, a locking bolt, locking means within the housing controlling the bolt, a reciprocatory closure for the housing having a key hole slot therein extending to the edge of the closure, through the enlarged portion of which the bolt normally reciprocates, the 25 bolt having therein a reduced portion which when projected to a plane common with the closure permits the narrow portion of the slot to be drawn past the bolt.

9. In a lock mechanism, a housing, a locking bolt, locking mechanism within the housing controlling the bolt, a closure for said housing locked by the bolt when the bolt is at either limit of its stroke and released by the adjustment of the bolt to an intermediate position.

10. In a lock mechanism, a housing, a bolt, lock mechanism within the housing controlling the bolt, a sliding closure for the housing having a projection engaged by the 40 bolt when in both locking and releasing positions but disengaged thereby when the bolt is in a predetermined intermediate position.

11. In a lock mechanism, a housing, a reciprocatory bolt, locking means within the 45 housing controlling the bolt, a closure for the housing, a shoulder on said closure normally engaging with the bolt to prevent the movement of the closure when the bolt is in both locked and unlocked positions, the bolt 50 being provided with a recess through which the said shoulder may pass in the opening or closing movement of the closure when said bolt is in a predetermined position.

12. In a lock mechanism, a housing, an 55 operating bolt, locking means within the housing controlling the bolt, a closure member for said housing controlled by the bolt, and a second closure member for the housing controlled by the first closure member.

60. 13. In a lock mechanism, a housing, a locking bolt, locking means within the housing controlling the bolt, a support for the housing with which the housing is slidably adjustable, and a reciprocatory member carried by the housing and engaging the sup-

port controlled by the bolt for preventing the detachment of the housing from its support.

14. In a lock mechanism, a housing, a locking bolt, locking means within the housing in which the housing is slidably movable, controlling the bolt, a support independent of the housing for the housing, attachment means for the support covered by the housing when the latter is in adjusted 75 position, and means for locking the housing to the support.

15. In a permutation lock, a housing, a bolt therein, a detent controlling the bolt, a partition in the housing of less length than 80 the housing, a plurality of independently adjustable spring actuated plungers controlling the detent, each plunger having an offset or shoulder thereon adapted to engage the end of said partition to limit the reciprocatory movement of the plungers under 85 the influence of their springs.

16. The combination with a lock mechanism of a permutation key comprising a main frame, a plurality of independently 90 adjustable plungers mounted in the frame, a series of ratchet teeth upon each plunger, and an independent detent pawl for each plunger engaging the ratchet teeth to hold the plunger in its adjusted position. 95

17. The combination with a lock mechanism of a permutation key therefor comprising a main frame, a plurality of reciprocatory plungers therein, a spring detent for each plunger permitting the independent adjustment of the plungers in one direction 100 but resisting the return movement of the plungers, and means for simultaneously releasing the detents.

18. The combination with a lock mechanism of a permutation key therefor comprising a main frame, a plurality of reciprocatory plungers therein, a spring detent for each plunger permitting the independent adjustment of the plungers in one direction 110 but resisting the return movement of the plungers, and a movable support common to all the detents.

19. The combination with a lock mechanism including a plurality of independent 115 movable locking units adapted to be moved to different predetermined positions to effect the release of the locking mechanism, of a key therefor comprising a series of independently adjustable plungers, each of the 120 plungers being provided with a series of notches, and a series of spring fingers one for each plunger engaging the said teeth to maintain the plungers in adjusted positions.

20. The combination with a lock mechanism including a plurality of independent movable locking units adapted to be moved to different predetermined positions to effect the release of the locking mechanism, of a key therefor comprising a series of inde- 125

pendently adjustable plungers, each of the plungers being provided with a series of notches, and a series of spring fingers one for each plunger engaging the said teeth to 5 maintain the plungers in adjusted positions, a reciprocatory slide upon which the fingers are carried, and a transverse cam bar with which the fingers are engaged by a reciprocatory movement of the slide to lock the 10 fingers in engagement with the plungers.

21. The combination with a lock mechanism of a permutation key therefor comprising a main frame, a plurality of reciprocatory plungers therein, a spring detent for 15 each plunger permitting the independent adjustment of the plungers in one direction but resisting the return movement of the plungers, a locking bar upon said frame, a support common to all the detents, said 20 locking bar and support being relatively adjustable whereby the locking bar and detents will be brought into engagement one with the other to lock the plungers in adjusted position.

22. The combination with a lock mechanism of a permutation key therefor comprising a main frame, a plurality of reciprocatory plungers therein, a spring detent for 25 each plunger permitting the independent adjustment of the plungers in one direction but resisting the return movement of the plungers, and a support common to all the detents capable of oscillatory movement adapted thereby to simultaneously release 30 all the detents.

23. The combination with a lock mechanism including a plurality of independently 35

movable locking members adapted to be moved to different predetermined positions to effect the release of the lock, of a permutation key comprising a plurality of independently adjustable plungers one for each locking member capable of adjustment to different relative positions corresponding with the releasing positions of the lock 40 members, an independent detent for each plunger adapted to retain the plunger in its adjusted position, means for simultaneously locking the detents in engagement with the plungers and means for simultaneously releasing the detents.

24. The combination with a lock mechanism including a plurality of independently movable locking members adapted to be moved to different predetermined positions 45 to effect the release of the lock, of a permutation key comprising a plurality of independently adjustable plungers one for each locking member capable of adjustment to different relative positions corresponding 50 with the releasing positions of the lock members, a series of ratchet teeth upon each plunger and an independent spring actuated detent engaging the teeth of each plunger to maintain the plungers in adjusted positions.

In testimony whereof, I have hereunto set my hand this 5th day of February A. D. 1915.

THOMAS A. SAMMONS.
